UNITED STATES PATENT OFFICE.

VICTOR KOBLER, OF ZURICH, SWITZERLAND.

TOBACCO PIPE.

Application filed December 11, 1922. Serial No. 606,229.

To all whom it may concern:

Be it known that I, VICTOR KOBLER, a citizen of the Republic of Switzerland, residing at Zurich, Switzerland, have invented certain new and useful Improvements in Tobacco Pipes, of which the following is a specification, reference being had therein to the accompanying drawing.

The present invention relates to improvements in tobacco pipes which are provided with baffles inserted in the stem for the purpose of delaying the smoke on its way from the bowl to the mouthpiece. Hitherto such baffles were also intended to cause the cooling and the purifying of the smoke, good results are, however, not obtainable with such constructions, as only a small percentage of nicotine and tobacco juice are deposited on the baffles. Further the precipitation of nicotine on the baffles renders the cleaning of the part inserted in the stem of the pipe difficult. When the precipitation of nicotine has reached a certain degree the smoke passing this precipitation is badly influenced by it.

The tobacco pipe according to the present invention shows the characterizing feature that the baffles or discs provided with apertures through which the smoke passes are spaced at such a distance from each other that upon immersing the inserted piece in a liquid the latter adheres in the recesses between the baffles owing to capillary action. In this manner the possibility is provided of causing the smoke to pass over liquid surfaces in many cells, whereby the cooling and the purifying action on the smoke is increased and the inserted part itself is cooled.

Several constructional examples of a tobacco pipe according to the present invention is illustrated in the accompanying drawings, in which:

Fig. 1 shows in a longitudinal section a first constructional example,

Fig. 2 is a cross-section along line I—I of Fig. 1,

Figs. 3 and 4 show the inserted part in two views taken at right angles to each other,

Fig. 5 shows in a longitudinal section a second constructional example,

Fig. 6 is a cross-section along line II—II of Fig. 5,

Fig. 7 shows a top view of Fig. 5, a bush inserted in the bowl being removed,

Fig. 8 is a plan view of the bush,

Fig. 9 shows the inserted piece fixed to the mouthpiece and withdrawn from the stem, and

Fig. 10 illustrates a detail variation. Referring now to the drawings throughout the various constructional examples 1 denotes a rod, i. e. the core of the part inserted in the stem and 2 designates a number of discs or baffles spaced from each other at a uniform distance.

In the first constructional example illustrated in Figs. 1—4 the members 3 and 4 arranged at two ends of the rod 1 have a greater width than the baffles 2 and the distances between the members 3 and 4 and the adjacent baffle 2 respectively are larger than the distance between every two baffles 2. The baffles 2 are shaped as circular discs.

As will be seen in Figs. 1 and 2 the inserted part is pushed into a tube 5 lining the bore of the stem, the inside diameter of the tube 5 corresponds to the diameter of the discs 2 so that the latter form a close fit in the tube 5 which is closed by a wall 5' at the end pointing towards the bowl. A bush 6 having a bottom is screwed into the bowl and is provided with a central bore in its bottom, the space inside the bush 6 serving to take up the tobacco is in communication with the foremost chamber formed between the member 3 and the adjacent disc 2 by an aperture 5'' provided in the tube 5. The discs 2 and the member 7 are provided at their periphery with two small slots 7 and the inserted part is so turned relatively to the stem that slots are at the top. The corresponding slots 7 in the discs 2 are in alignment so that two channels are formed by all the slots 7 extending parallel to the rod 1. By means of these channels the chambers formed by every two discs 2 inside the tube 5 intercommunicate. The chamber remote of the bowl is connected by means of the slots 7 in the member 4 with the bore of the mouth-piece.

Previous to using the pipe the mouthpiece is removed and the inserted part is withdrawn from the stem of the pipe by gripping the member 4 and is then immersed in a liquid. When the inserted part is withdrawn from the liquid some of the liquid adheres to the discs owing to capillary action and fills out to some extent the recesses between adjacent discs, as is indicated in Figs. 3 and 4, the liquid collecting in the lower half of the recesses so that upon insertion of the part into the stem a plurality

of chambers partly filled with liquid and subdivided by the discs 2 are formed. Water may be used as liquid for immersing the inserted part in.

- 5 The inserted part as well as the bushes 5 and 6 are preferably made of aluminium, which besides having a small weight presents the advantage of being not attacked by the tobacco juice and of being easily cleaned.
- 10 The smoke leaving the bowl by the aperture 5" enters below the bush 6 into the foremost chamber and flows through the slots 7 from one chamber to the next. The smoke gets into touch with the surface of
- 15 the liquid and is thereby subjected to an effective cooling action and from the beginning of its travel, i.e. when the smoke is still hot, volatile nicotine is effectively absorbed. The liquid causes further a cooling of the inserted part. From time to time the inserted part is withdrawn to be cleaned from the adhering matter and to renew the liquid.

20 The second constructional example differs from that described above inasmuch as several of the discs on the inserted part are situated immediately below the bowl of the pipe. A bush 6 is again inserted in the bowl, in which bush the tobacco is filled. The

25 bush 6 has a bottom provided with radial slots 6' through which the smoke passes.

30 The inserted part is connected by means of an extended end member 4 with the mouth-piece of the pipe and it can be withdrawn by withdrawing the mouthpiece. The handling of the inserted part for cleaning the latter and the renewal of the liquid is facilitated thereby. The end disc 3 has the shape of a curved head. The discs are

35 provided with three slots 7 and the respective slots of all the discs are in alignment.

40 The cooling and the purifying of the smoke occurs in the same manner as described above.

45 In the constructional example illustrated in Fig. 10 the tube 5 forms the stem of the pipe and is fixed to a cylindrical metal cup 8. The bowl 9 is held by the cup 8 and the inserted part consisting of the core 1 provided with the discs 2 does not project into the interior of the cup 8.

I claim:

1. A tobacco pipe having a stem provided with a bore, and a part inserted in said

stem and consisting of a rod and discs on 55 said rod, spaced at such a distance from each other that upon the inserted part being immersed in a liquid the latter will adhere to said discs by capillary action and will span the intermediate spaces between adjacent 60 discs.

2. A tobacco pipe having a stem provided with a bore, and a part inserted in said stem and consisting of a rod and discs on said rod spaced at such a distance from each other 65 that upon the inserted part being immersed in a liquid the latter will adhere to said discs by capillary action and will span the intermediate spaces between adjacent discs, said discs being provided with slots, the respective 70 slots in the discs being arranged in alignment.

3. A tobacco pipe having a mouth-piece, a stem provided with a bore, and a part extending beneath the bowl of the pipe connected to said mouthpiece and fitting into the bore of said stem and consisting of a rod and discs on said rod spaced at such a distance from each other that upon the inserted part being immersed in a liquid the latter 75 will adhere to said discs by capillary action and will span the intermediate spaces between adjacent discs.

4. A tobacco pipe having a mouth-piece, a bowl, a stem provided with a bore, and a 80 part inserted in said stem and consisting of a rod and discs on said rod spaced at such a distance from each other that upon the inserted part being immersed in a liquid the latter will adhere to said discs by capillary 85 action and will span the intermediate spaces between adjacent discs, said discs being provided with slots and the respective slots in the discs being arranged in alignment one end of said rod terminating in a longitudinally slotted cylinder and the other end of the rod terminating in a member thicker than a disc.

5. In a tobacco pipe, a stem having a bore and a part inserted in said bore comprising 100 a central member and spaced discs on said member, the spaces between said discs forming capillary chambers for liquid, and said discs having radial slots disposed substantially horizontally.

105 In testimony whereof I affix my signature.

VICTOR KOBLER
